United States Patent Office

Des. 205,730
Patented Sept. 13, 1966

205,730

JUG

Richard L. Platte, Ann Arbor, Mich., assignor to Hoover
Ball and Bearing Company, Saline, Mich.

Filed Sept. 13, 1965, Ser. No. 86,963

Term of patent 14 years

(Cl. D58—5)

FIG. 1

FIG. 2

FIG. 3

FIG. 4

FIG. 5

FIG. 6

FIG. 7

FIG. 8

FIGURE 1 is a side elevational view of a jug showing my new design;

FIGURE 2 is a rear elevational view thereof;

FIGURE 3 is a side elevational view of the jug when rotated 45 degrees counter-clockwise from the position seen in FIG. 1;

FIGURE 4 is a top plan view thereof;

FIGURE 5 is a sectional view taken on the line 5—5 of FIG. 1;

FIGURE 6 is a sectional view taken on the line 6—6 of FIG. 1;

FIGURE 7 is a sectional view taken on the line 7—7 of FIG. 1; and

FIGURE 8 is a sectional view taken on the line 8—8 of FIG. 1.

The dominant features of my design reside in the portions shown in full lines.

I claim:

The ornamental design for a jug, as shown and described.
